MOVABLE TOY ON RAIL

Samuel L. Beder, New York, N. Y.

Application June 10, 1953, Serial No. 360,729

7 Claims. (Cl. 46—32)

This invention relates to a toy for young children and is more particularly concerned with a toy of this nature which is adapted to be used in cooperation with the rail of a play pen or crib to provide the child with a permanently available plaything.

Many toys have been proposed which are suitable for use by young children in play pens and cribs but it is common experience that the child frequently throws the toy out of the play pen or crib and the toy must be repeatedly returned to the child by the parent. Not only is this often annoying to the parent but the surroundings may be damaged by the toy in flight unless it is of a very soft and resilient material. Moreover, toys of the rolling type such as automobiles, trains and the like cannot generally be successfully played with by the child in the confines of the play pen or crib because of the small area available and because the bed clothes or the play pen pad do not provide a suitable surface for using this type of toy. As a result, the child is limited in the type of toy which he can use.

It is an object of the present invention to provide a toy for use by a young child in a crib or play pen which cannot be hurled away by the child.

It is another object of the invention to provide a toy of the character indicated which simulates a toy of the rolling type and which may be effectively and successfully used within the confines of the play pen or crib.

It is a further object of the invention to provide a toy for small children which is constructed to engage with the play pen or crib and to resist efforts of the child to dislodge it, yet is easily movable by the child along the crib or play pen rail to simulate the movements of a rolling toy.

It is another object of the invention to provide a toy for the child at the standing age which will encourage and stimulate him to walk.

It is a further object of the invention to provide a toy of novel construction which supplies an important need in the toy field.

It is another object of the invention to provide a toy of the type described which is economical to manufacture.

In accordance with the invention, there is provided a toy adapted to be used in association with the rail of a crib or play pen or the like which comprises a body, a pair of laterally spaced-apart legs or flanges which are adapted to embrace the sides of the rail, and a lock device which holds the toy against removal from the rail by the child but permits free longitudinal movement of the toy along the rail.

It is a feature of the invention that it makes possible the use of the rail of a play pen or crib as a play surface.

It is another feature of the invention that it provides a new type of toy for the young child while freeing the parent from the annoyance of chasing after toys hurled from the play pen or crib.

It is a further feature of the invention that the toy

2

will stimulate and encourage a child at the standing age to walk by reason of the fact that as the toy is pushed along the crib or play pen rail the child will be naturally inclined to walk over to the new position of the toy to push it further along.

Other objects and features of the invention will be readily apparent from the following detailed description of illustrative embodiments thereof and from the accompanying drawing, wherein,

10 Fig. 1 is a perspective view of a toy embodying features of the present invention, showing it in association with the rail of a conventional play pen or crib;

Fig. 2 is a front elevational view of the toy shown in Fig. 1;

15 Fig. 3 is an elevational view of the toy as seen from the bottom; and

Fig. 4 is a side elevational view of another embodiment of the invention.

Referring to the drawing, and more particularly to 20 Figs. 1 to 3, the reference numeral 10 designates generally the toy illustrated which, in the embodiment shown, is constructed to simulate a railroad locomotive. The locomotive 10 has a base 12 upon which is secured, as by screws 13, a boiler block 14 and a cab block 15 to define the body of the toy. To increase the locomotive appearance of the toy, the boiler block 14 has secured to it a headlight member 16 and dome elements 17. It will be apparent that the locomotive body illustrated is only one of many possible forms the body of the toy

25 may take. If desired, for example, the toy body may be in the form of an automobile, a ship, an airplane, or the like. The body is advantageously painted in bright colors to attract and please the child, and bells or other noise-makers may be attached to the toy to interest the child. In any case, the bottom of the base 12 is planar and smooth so that it will slide easily over the rail 20 of the crib or play pen, as shown in Fig. 1. Although only a portion of the rail is shown, it will be understood that the toy 10 is suitable for use with any conventional

30 play pen, e. g. having three or four sides with a top rail, and with a conventional crib, e. g. having a foot board and a head board and two sides formed with top rails. The rails in both cases are positioned on uprights or balusters which are of lesser width than the rails so

35 that the sides of the rails overhang the uprights. Depending from each side of base 12 and embracing the sides 22 of the rail 20 shown in Fig. 1 are parallel legs 24 and 25 which, in the embodiment illustrated, are in the form of sheets which are sufficiently wide to extend well below the bottom of the rail 20. The legs 24 and 25 are secured, as by screws 26, to the base 12 and serve as a support for attaching the wheels 28 of the locomotive. The wheels 28 may be rotatable or non-rotatable since they are merely for purposes of appearance and do not support the toy. The legs 24 and 25

50 guide the toy 10 laterally so that it follows the rail 20 at all times and permit the toy to be moved backwards and forwards at will. For use on an arcuate rail, as in a circular play pen, the legs 24 and 25, instead of being 55 planar as shown, are advantageously curved to conform to the curvature of the rail.

It will be obvious that the toy as thus described could be easily removed from the rail by the child. To prevent this and yet to permit the parent to remove the toy when 60 desired, there is provided a spring locking element which is positioned to engage the bottom of the rail 20 and to resist upward movement of the top from the rail. In the embodiment illustrated in Figs. 1 to 3, the locking element is in the form of a bowed spring strip 30 which is 65 formed from spring steel or other convenient material and which is fixedly secured at one end to the leg 25, as by a screw or rivet indicated at 33, and is provided with

70

a slot 34 at its other end in which a pin 35 is adapted to engage. When the spring strip 32 is in its normally bowed position, as in Figs. 1 and 2, the pin 35 engages the outer end of slot 34. This slot, however, permits the spring to be pressed flat against the leg 25 by the parent to permit removal of the toy from the rail. When, however, the spring strip 30 is released, it assumes its bowed position and underlies the rail 20, sliding against the uprights or balusters 40 of the crib or play pen. It will be understood that the distance between the end of pin 35 and the inside surface of leg 24 is at least as great as the width of rail 20 but that it is not substantially greater than this distance in order that at all times the spring strip 30 will underlie the rail when it is in released position with the leg 24 pressed against the side of the rail. When the toy is placed on the rail, it is mounted with the leg carrying the spring strip on the outside to increase the difficulty of access by the child.

To place the toy on the rail it is merely necessary to press the center of the spring strip and to slide the two legs over the rail. To remove the toy from the rail, the spring strip is again pressed flat and held in this position until the toy has been pulled upwardly a sufficient distance that the spring strip is no longer below the bottom of the rail, then the toy is pulled off the rail. While the toy may thus be applied to and removed from the rail by an adult, the locking device is sufficiently difficult that it will effectively resist the efforts of a young child. As a result, to the child the toy will be permanently mounted on the crib or play pen rail, yet he will be able to move it freely back and forth on the rail. The child will thus have a plaything which will give him many hours of pleasure and which he will not be able to dislodge and throw away from his enclosure. At the same time, the annoyance to the parent of having to pick up toys repeatedly thrown from the crib or play pen will be avoided.

It will be apparent that various changes may be made in the embodiment illustrated in Figs. 1 to 3 without departing from the spirit and scope of the invention. One modified form is shown by way of example in Fig. 4 which illustrates a toy having the body and leg construction of the embodiment of Figs. 1 to 3 but having an alternative form of spring locking element. In this embodiment, the bowed spring locking element 45 is fixedly secured at one end, as by a screw or rivet indicated at 46, to leg 25 and has secured to it at its other end a pin 47 which carries a knob 48 which lies exteriorly of leg 25. The pin 47 passes through a slot 50 in leg 25. By reason of the slot 50, the spring 45 can be flattened upon moving the knob away from the fixed point 46. Upon release of the knob 48 the spring element 45 snaps back into its bowed position underlying the crib rail.

It will be obvious that other changes and modifications may be made without departing from the appended claims and it is intended, therefore, that all matter contained in the foregoing description and in the drawing shall be interpreted as illustrative only.

I claim:

1. A toy for use in combination with the rail of a play pen, crib and the like comprising, in combination, a body portion having a lower surface for engagement with the top surface of the rail for free sliding movement thereover, depending laterally spaced-apart legs extending from said lower surface a distance substantially greater than the width of said lower surface between said legs, said legs being positioned to overlie the sides of the rail when said lower surface is in engagement with the rail and having portions extending downwardly therefrom, said legs defining with said body portion an elongated channel for reception of said rail, said channel being of substantially rectangular cross-section with a top defined by said lower surface of the body portion, sides defined by said downwardly-extending portions, and being open at the bottom, and retaining means positioned in one of

said downwardly-extending portions for engagement with the under surface of said rail, said retaining means being manually displaceable out of engagement with said rail lower surface and while engaging said under surface permitting free sliding movement of said toy over said rail.

2. A toy for use in combination with the rail of a play pen, crib and the like comprising, in combination, a body portion having a lower surface for engagement with the top surface of the rail for free sliding movement thereover, depending laterally spaced-apart legs extending from said lower surface a distance substantially greater than the width of said lower surface between said legs, said legs being positioned to overlie the sides of the rail when said lower surface is in engagement with the rail and having portions extending downwardly therefrom, said legs defining with said body portion an elongated channel for reception of said rail, said channel being of substantially rectangular cross-section with a top defined by said lower surface of the body portion, sides defined by said downwardly-extending portions, and being open at the bottom, and spring retaining means positioned in one of said downwardly-extending portions of said legs for engagement with the under surface of said rail, said spring retaining means being manually displaceable out of engagement with said rail lower surface and while engaging said under surface permitting free sliding movement of said toy over said rail.

3. A toy for use in combination with the rail of a play pen, crib and the like comprising, in combination, a body portion having a lower surface for engagement with the top surface of the rail for free sliding movement thereover, depending laterally spaced-apart legs extending from said lower surface a distance substantially greater than the width of said lower surface between said legs, said legs being positioned to overlie the sides of the rail when said lower surface is in engagement with the rail and having portions extending downwardly therefrom, said legs defining with said body portion an elongated channel for reception of said rail, said channel being of substantially rectangular cross-section with a top defined by said lower surface of the body portion, sides defined by said downwardly-extending portions, and being open at the bottom, and spring retaining means positioned in one of said downwardly-extending portions of said legs for engagement with the under surface of said rail, said spring retaining means being manually displaceable out of engagement with said rail lower surface and while engaging said under surface permitting free sliding movement of said toy over said rail.

4. A toy for use in combination with the rail of a play pen, crib and the like comprising, in combination, a body portion having a lower surface for engagement with the top surface of the rail, depending laterally spaced-apart legs extending from said lower surface a distance substantially greater than the width of said lower surface between said legs, said legs being positioned to overlie the sides of the rail when said lower surface is in engagement with the rail and having portions extending downwardly therefrom, and a spring strip retaining means positioned on the inner surface of one of said downwardly extending portions of said legs for engagement with the under surface of said rail, said spring strip being fixedly secured at one end to said downwardly-extending portion and having a slot at its other end and said downwardly-extending portion carrying a pin engaged in said slot, whereby said spring strip is manually displaceable out of engagement with said rail lower surface.

5. A toy for use in combination with the rail of a play pen, crib and the like comprising, in combination, a body portion having a lower surface for engagement with the top surface of the rail, depending laterally spaced-apart legs extending from said lower surface a distance substantially greater than the width of said lower surface between said legs, said legs being positioned to overlie the sides of the rail when said lower surface is in engage-

ment with the rail and having portions extending downwardly therefrom, and a spring strip retaining means positioned on the inner surface of one of said downwardly extending portions of said legs for engagement with the under surface of said rail, said spring strip being fixedly secured at one end to said downwardly-extending portion and carrying a pin at its other end and said downwardly-extending portion being formed with a slot in which said pin is received, whereby said spring strip is manually displaceable out of engagement with said rail lower surface.

6. In combination with the rail of a play pen crib and the like, a toy slidable over said rail, said toy comprising a body portion having a lower surface for engagement with the top surface of the rail for free sliding movement thereover, depending laterally spaced apart legs extending from said lower surface a distance substantially greater than the width of said lower surface between said legs, said legs being positioned to overlie the sides of the rail when said lower surface is in engagement with the rail and having portions extending downwardly therefrom, said legs defining with said body portion an elongated channel for reception of said rail, said channel being of substantially rectangular cross-section with a top defined by said lower surface of the body portion, sides defined by said downwardly-extending portion, and being open at the bottom, and retaining means positioned in one of said downwardly-extending portions for engagement with the under surface of said rail, said retaining means being manually displaceable out of engagement with said rail lower surface and while engaging said under surface permitting free sliding movement of said toy over said rail.

7. In a play pen, crib and the like having a side wall formed with a top rail and a plurality of uprights supporting said rail, a toy slidable over said rail, said toy comprising a body portion having a lower surface for engagement with the top surface of the rail for free sliding movement thereover, depending laterally spaced apart legs extending from said lower surface a distance substantially greater than the width of said lower surface between said legs, said legs being positioned to overlie the sides of the rail when said lower surface is in engagement with the rail and having portions extending downwardly therefrom, said legs defining with said body portion an elongated channel for reception of said rail, said channel being of substantially rectangular cross-section with a top defined by said lower surface of the body portion, sides defined by said downwardly-extending portions, and being open at the bottom, and retaining means positioned in one of said downwardly-extending portions for engagement with the under surface of said rail, said retaining means being manually displaceable out of engagement with said rail lower surface and while engaging said under surface permitting free sliding movement of said toy over said rail.
